CLAIM

The ornamental design for an integrated swim cap and goggles, as shown and described.

DESCRIPTION

FIG. 1 is a front view of the design;

FIG. 2 is a rear view of the design;

FIG. 3 is a left side view of the design, and the right side view is a mirror image of FIG. 3;

FIG. 4 is a top view of the design, and the bottom view is a mirror image of FIG. 4;

FIG. 5 is a perspective view of the design viewed from above; and,

FIG. 6 is a perspective view of the design viewed from below.
